UNITED STATES PATENT OFFICE.

HENRY LESLY, OF BIRMINGHAM, ALABAMA.

RAILWAY-SWITCH.

SPECIFICATION forming part of Letters Patent No. 395,066, dated December 25, 1888.

Application filed October 11, 1888. Serial No. 287,866. (No model.)

To all whom it may concern:

Be it known that I, HENRY LESLY, of Birmingham, in the county of Jefferson and State of Alabama, have invented a new and Improved Railway-Switch, of which the following is a full, clear, and exact description.

Reference is to be had to the accompanying drawings, forming a part of this specification, in which similar letters of reference indicate corresponding parts in all the figures.

Figure 1 is a plan view of my new and improved railway-switch. Fig. 2 is a sectional elevation of the same on line $x-x$ of Fig. 1. Fig. 3 is a similar view taken on line $y-y$ of Fig. 1; and Fig. 4 is a transverse sectional view on line $z-z$, Fig. 1.

The invention will first be described in connection with the drawings, and then pointed out in the claims.

In the drawings I have shown two switch-frames, A A, each composed of two pointed rails, $a a$, connected together by cross-pieces $c c$ and c' . The said frames are each pivoted between the rails B B' C C by a bolt, d^2 , passing through the center of the cross-piece c' , so that the blunt ends of the rails $a a$ abut against the ends of the said rails C C.

The two frames A A are operated for opening and closing the switch by the lever D, fulcrumed on shaft D', journaled in the blocks D ^{2} D ^{2} at the side of the track. The lever D is formed with an enlarged head, d , and connected to this head by the studs $d' d'$, on opposite sides of the shaft D', are the connecting-rods D ^{3} D ^{3} . These connecting-rods pass under the rail B and are connected to the arms E E of the switch-frames A A. By turning the lever D the two rods E E are simultaneously operated in opposite directions. Each of the connecting-rods D ^{3} may be connected to the arm E or disconnected therefrom at pleasure, so that either switch-frame A may be operated independently of the other by the same lever, D, or both switch-frames may be operated simultaneously in opposite directions by the lever D, if desired.

The ends of the connecting-rods D ^{3} may be connected to the arms E in various ways to permit ready connection and disconnection; but I prefer to slot the arms E both vertically and horizontally, as shown at $e e'$, to form the projection e^2 at the end of each arm, as shown

clearly in Fig. 2. The ends of the connecting-rods E are notched to form the hooks f and shoulders or offsets f' , (see Fig. 4,) and they are placed in the slots $e e'$. By shifting the connecting-rods E laterally in the said slots e' they may be made to engage with or disengage the projections e^2 , as shown in Fig. 2. When moved in line with the vertical slot e , as shown at the right in Fig. 2, the connecting-rods move independently of the switches. When moved out of line with the said vertical slots, as shown at the left in Fig. 2, the movement of the connecting-rods operates the switches. Normally, the said connecting-rods D ^{3} are held to engage the arms E by coiled springs F on rods F', the springs acting between fixed collars g on the rods and the sliding washers g' on the said rods F. For drawing or moving the said rods from under the projections e^2 to disconnect the rods from the arms E, I use the levers G, pivoted outside of the track and connected by cords or wires G' G' to the connecting-rods D ^{3} . The said cords or wires pass around the pulleys H, so that when the levers G are turned outward away from the track the said connecting-rods will be drawn out from under the projections e^2 into the vertical slots e , thus effecting the desired result of disconnecting the said connecting-rods from the switch-frames. The levers G may be held back by pins h, and by removing these pins the springs will automatically force the connecting-rods over to engage with the arms E. The cords G' might be connected directly to the connecting-rods D ^{3} ; but I prefer to use the T-pieces or blocks m, passed through slots m' in the connecting-rods D ^{3} , as shown clearly in Fig. 4, so that the said cords may be fastened to the outer ends of said T-pieces or blocks.

Having thus described my invention, what I claim as new, and desire to secure by Letters Patent, is—

1. The pivoted switch-frame A, comprising pointed rails a and suitable cross-pieces, and provided with an arm, E, formed with slots $e e'$ and projection e^2 , in combination with the connecting-rod D ^{3} , formed with notched end $f f'$, the rod F', and spring F, to act upon the said connecting-rod, and the operating-lever D, substantially as described.
2. The combination of the operating-lever

D, connecting-rod D³, having shoulders f f', rod F', spring F, placed thereon to act upon the connecting-rod, the arm E, switch-frame A, lever G, cord G', attached to lever G, and connecting-rod D³, and pulley H, the arm E being formed with vertical and horizontal slots to form projection e², substantially as and for the purposes set forth.

3. The two switch-frames A A, arms E E, and laterally-shifting connecting-rods D³, arranged to be connected to and disconnected

from the arms E E, in combination with the single operating-lever D, to which the rods D³ D³ are connected, the levers G G, and cords G', passing over the pulleys H, substantially as described. 15

HENRY LESLY.
